Patented May 30, 1922.

UNITED STATES PATENT OFFICE.

WILLIAM L. WALKER, OF NEW YORK, N. Y.

SOUND-RECEIVING APPARATUS.

1,417,786.

Specification of Letters Patent. Patented May 30, 1922.

Application filed November 19, 1917. Serial No. 202,680.

To all whom it may concern:

Be it known that I, WILLIAM L. WALKER, a citizen of the United States of America, and resident of New York, in the county of 5 New York and State of New York, have invented new and useful Improvements in Sound-Receiving Apparatus, of which the following is a specification.

This invention relates to sound signaling 10 and more particularly to submarine signaling and to the detection of sounds in water. The invention comprises a device which is a more efficient transmitter of impulses and which consists of a diaphragm of large dimensions. Instead of forming an integral 15 part of the microphone itself of a part of a ship's hull the diaphragm forms one side of a sound box and may be balanced by air pressure to compensate for external water 20 pressure as set forth in my previous applications Serial No. 161,179, filed April 11, 1917, Patent No. 1,349,305, dated Aug. 10, 1920, and Serial No. 176,299, filed June 22, 1917. By this method an exceedingly thin 25 and sensitive diaphragm may be used which will respond to very faint or weak sound waves.

Heretofore in employing microphones in submarine signaling it has been customary 30 to employ so-called "solid back microphones", that is, microphones having the back or body portion rigidly mounted on a stationary support. This is unsatisfactory for general submarine signaling, where 35 it is frequently desirable to detect very faint sounds coming from long distances, for the reason that if the microphone be made sufficiently sensitive to detect faint sounds it is subject to injury or destruction 40 by heavy sounds produced near the microphone. It has been proposed to attach the diaphragm of a microphone to a vibratory sound-receiving device and to leave the body of the microphone unattached, so that the 45 body can move with the diaphragm when heavy sounds are received and thereby avoid undue displacement of the diaphragm relatively to the body. While this reduces the danger of injury to the microphone, it 50 also reduces to a large extent the sensitivity of the microphone.

It is the object of the present invention to overcome the aforesaid difficulties and not only to eliminate the danger of injury to the microphone from heavy sounds nearly but also to maintain high sensitivity of the microphones to faint sounds from long distances. In other words it is the object 55 of this invention to provide a microphone which is substantially free from the dangers incident to solid-back microphones but which is substantially as sensitive as solid-back microphones.

In one aspect the present invention comprises a microphone cell having its diaphragm connected to a vibratory sound-receiving device and having its body portion free to move with the diaphragm together with means for yieldingly restraining or damping movement of the body of the 60 microphone. The preferred form of damping means comprises an air vane or baffle plate connected to the microphone body so that movement of the microphone is restrained by the air resistance of the air 65 vane, the air vane being arranged to operate either in the open air or as a piston in a cylinder.

Another phase of the present invention involves pivotally supporting the current-varying or current-generating device so 70 that the device may be readily actuated by the sound responsive device with a minimum of frictional resistance and without supporting the current-varying device upon the 75 sound-responsive device. This method of supporting the current-varying device permits the utilization of a plurality of such devices in cooperative relationship with a single sound-responsive device. 80

The sound-responsive diaphragm is connected to a lever which oscillates in synchronism with the diaphragm. The lever associated with the sound-responsive diaphragm is preferably mounted on a knife-edge support so as practically to eliminate friction and lost motion, the elimination of lost motion being particularly important inasmuch as the amplitude of vibration of the parts may be as low as one-tenth of 95 100 millimeter. Attached to this lever is one or more adjustable weights, together with

dragging or damping devices and one or more microphonic cells, that is a cell having the electrodes of the microphone of the pressure type, but without the usual external diaphragm. These cells are energized in the usual manner by a battery and transmit the energy received by current variation to a telephone receiver or other recording apparatus.

10 Microphones attached to ships are often affected more by the disturbing noises set up in the ship's hull, such as the action of the waves, the travel of the ship, or the noise of the machinery than by the energy originating from the sound waves; and in order to reduce the effect of these disturbances, this apparatus can be acoustically tuned by weights and dampers without cutting off other sound waves.

15 20 In the accompanying drawings:—

Figure 1 is a side elevation of one embodiment of the invention, parts being shown in section;

25 Figure 2 is a side elevation of a modified embodiment of the invention, parts being shown in section;

Figure 3 is a side elevation of another modification of the invention; and

30 Figure 4 is a side elevation of a lever arm carrying a plurality of microphones.

The embodiment shown in Fig. 1 comprises a sound-responsive device in the form of a diaphragm 1 which may be secured in an opening O in the side of a ship or in a sound box, and two current-varying devices in the form of microphones 2 and 3. The microphones are supported on a lever 4 which is pivotally mounted, preferably at its central point, on a knife-edge support 5. The lever arm 4 is connected to the diaphragm 1 by means which preferably includes a short flexible strip of metal 7 adapted to compensate for the slight vertical component of movement of the lever arm resulting from its rotary movement about the knife-edge support.

The microphones consist of cells having the electrodes of microphones of the pressure type and the cells are preferably mounted by means of insulators. Thus the microphones 2 and 3 comprise diaphragms 8 and 9 and cup-shaped cells 10 and 11 which contain particles of carbon. The diaphragms 8 and 9 may be held over the openings of the cup-shaped cells in any suitable manner, as for example, by means of the overhanging flanges shown in the drawing. The microphones 2 and 3 are mounted through the medium of their diaphragms by means of rods 14 and 15, which are preferably of insulating material such as ivory or hard rubber, extending between the lever arm 4 and the central points of the diaphragms. Weights in the form of rods 16 and 17 are preferably threaded or otherwise

detachably mounted on the carbon cup for the purpose of regulating the weight and inertia of the cup. The rods 16 and 17 rest on bearings 12 and 13 which support the weight of the rod and microphone cells, the 70 bearings 12 and 13 preferably being disposed in the region of the center of gravity of the rods and cells taken together so that the rods and microphones are substantially balanced upon the bearings.

75

The sound responsive diaphragm 1, microphones 2 and 3, lever 4, etc., constitute an oscillatory system, the diaphragms 1 supplying the necessary resilience, and I preferably provide some means for regulating 80 the period of this vibrating or oscillatory system. Suitable means for this purpose comprises one or more weights 30 adjustably mounted on the lever arm 4. As the weights are moved toward the pivot 5 the 85 effective weight of the system is reduced and the period is decreased and by moving the weights away from the pivot the inertia of the system is increased and the period is increased.

90

95 The embodiment shown in Fig. 2 comprises a sound-responsive device in the form of a diaphragm 18 and microphone cell 20 mounted on the sound-responsive device 18 through the medium of an insulating connection 22, together with means for regulating the freedom of movement of the body of the microphone cell. This means comprises a cylinder 23 connected with the body of the microphone through the medium of a 100 piston rod 25, the piston, cylinder, microphone and sound-responsive device preferably being disposed collinearly. A number of small holes 21 are provided in the piston or a by-pass 26 is provided around the piston, or both may be provided, to afford a communication between the opposite ends of the cylinder, the by-pass 26 preferably being provided with a valve 27 to regulate its effective cross-sectional area. The cylinder 105 23 may be filled with any suitable fluid which is adapted to retard the movement of the piston longitudinally of the cylinder, the character of the fluid determining the resistance offered to the movement of the piston and microphone body. For example, a liquid would afford a greater resistance to the movement of the piston than would a gas. For most purposes air is satisfactory, the density of the air determining the degree of resistance offered to movement of the piston. A suspension rod 31 containing an insulation section 32 may be provided to support the cylinder and hold it in fixed position.

110

115 120 125 The embodiment shown in Fig. 3 comprises a sound-responsive diaphragm 33, a microphone 34 joined to the sound-responsive diaphragm in a manner similar to that illustrated in Fig. 1, a lever 35 for pivotally 130

supporting the microphone at least in part, and damping or dragging means in the form of a disk 36 mounted on the rear of the microphone cell 37. The lever 35 may be 5 provided with an adjustable weight 37 as in Fig. 1 and the microphone is preferably insulated from its support by means of an insulating connection 38. The disk 36 prevents a rapid oscillation of the microphone 10 by virtue of the large air resistance which it affords, but at the same time it permits a slow movement of the parts of the microphone when heavy disturbances reach the microphone. To regulate the drag produced 15 by the disk its effective size may be varied or by varying the size of openings therein or by interchanging disks of different sizes. Obviously the disk of Fig. 3 would offer less resistance to the movement of the carbon cup 20 than would the piston 24 of Fig. 2, especially when the cylinder of Fig. 2 is filled with a liquid. Thus the apparatus of Fig. 2 will respond to lower frequencies than will the apparatus illustrated in Fig. 3, especially 25 when the cylinder is filled with a liquid.

Fig. 4 illustrates one way of associating a relatively large member of microphone cells with a lever arm and at the same time 30 causing them to be affected equally by vibrations of the oscillating arm so that they may be connected either in parallel or in series. On each end of the lever arm 39 is a cross-arm 40 carrying a plurality of microphone 35 cells 41 in a manner similar to that shown in Fig. 1, each of the cells being connected to the lever arm through the medium of its diaphragm and all of the microphones being substantially equidistant from the lever pivot. Any suitable dragging means may be 40 associated with the cells as illustrated for example in Figs. 1 to 3 for the purpose of rendering them responsive only to vibrations of particular frequencies. It will be understood that ordinary microphone cells 45 are very light and by making the supporting, connecting and dragging parts correspondingly light the system can be vibrated at a relatively high frequency even when carrying a number of microphone cells as shown in Fig. 4.

The operation of the apparatus is as follows: When sound waves impinge on the diaphragm 1 the diaphragm is vibrated back and forth, causing the lever arm 4 to oscillate correspondingly. The microphones 2 and 3 mounted on the lever arm will tend to move with the lever arm, and the degree of movement of the microphones will be determined 50 by the rate of vibration of the lever arm and the weight of the body portions of the microphones. If the lever arm vibrate slowly the microphones will move substantially as much as the lever arm. On the

other hand, if the lever arm vibrate at a 65 relatively high frequency the weights 16 and 17 attached to the microphones will prevent them from following the movement of the lever arm, whereby the diaphragms of the microphones will be flexed back and forth so 70 as to vary the current flowing through the microphones. By changing the size of the weights 16 and 17, the relative movement between the body portions and diaphragms of the microphones can be regulated so as 75 to regulate the range of sounds through which the microphones will be appreciably responsive.

Another factor determining the relative movement between the body portions of the 80 microphones and the diaphragms of the microphones is the stiffness of the latter. If the diaphragms be relatively heavy and stiff, the body portions of the microphones will follow the diaphragms at higher fre- 85 quencies than if the diaphragms be relatively thin and flexible.

Fig. 2 illustrates the fact that the microphone may be mounted directly on the sound-responsive diaphragm instead of upon 90 the pivoted lever. However, the lever support is preferable for most purposes, inasmuch as it relieves the sound-responsive diaphragms from the weight of the microphones without adding appreciably to the 95 resistance to the movement of the microphone diaphragms. The lever arm also makes it possible to acutate any desired number of microphones from a single sound-responsive device. By disposing the microphones equidistantly from the pivot point 100 the microphones are equally effected.

In Fig. 1 only two microphones are associated with the diaphragm 1, but any desired number, depending upon the length 105 of the lever arm, could be employed as illustrated in Fig. 4. By virtue of the microphone being mounted on opposite ends of the lever arm they operate correspondingly. They may be connected either in parallel or 110 series, and an audion or other amplifying device may be employed in conjunction therewith. Obviously the sound-responsive diaphragms may be utilized to receive sound impulses transmitted either through the air 115 or through water. When employing the apparatus for submarine sound detection the diaphragms may be mounted in sound boxes in any suitable manner or they may comprise the shell of a ship; that is, the rods 6 120 and 22 may, if desired, be connected to the shell of the ship instead of to diaphragms.

The operation of the structure shown in Fig. 3 is similar to that of Figs. 1 and 2, the air resistance of the disk serving to damp the vibration of the microphone. The piston 24 in Fig. 2 and disk 33 in Fig. 3 each constitutes a damping vane, the chief difference

between the two being that the former moves in a closed space whereas the latter moves in the open:

While I preferably connect the diaphragm 5 of the microphone cell with the sound-responsive device it is to be understood that when employing dragging means as above described the parts may be reversed. That is, the carbon cup may be connected to the 10 sound-responsive diaphragm and the damping or dragging means may be connected to the diaphragm of the microphone cell.

From the foregoing it will be evident that my improved apparatus is peculiarly adapted 15 to receive sound waves throughout a certain range of frequencies and at the same time to be substantially unresponsive to sound disturbances which are not included within the predetermined range. Thus I may receive 20 comparatively feeble signals within the limited range of frequencies from a distance notwithstanding the concomitant occurrence of loud noises outside the limited range either at short or long distances. And inasmuch as most interfering noises are of relatively low frequencies my apparatus is comparatively free from disturbances, whereas fixed back microphones are subject to great liability of injury from loud noises nearby. 25 By utilizing the principle of inertia together with a damping or dragging effect according to the present invention signals or sounds of certain character may be received from variable distances throughout a wide 30 range of intensities without substantial liability of injury or disturbance to the microphones.

I claim:—

1. In a sound detecting apparatus, a 40 sound receiver, a microphone comprising a cell provided with a diaphragm, cooperative electrodes mounted upon the cell wall and diaphragm respectively, means connecting the diaphragm directly to said sound receiver, means supporting said cell for movement with said receiver, and means for damping the movement of said cell so that when said sound receiver moves slowly both of said electrodes are moved slowly with 45 the sound receiver but with substantially no relative movement therebetween, and when the sound receiver moves rapidly the electrode carried by the diaphragm is moved relatively to the other electrode, said other 50 electrode being restrained from movement 55 by said damping means.

2. In a sound detecting apparatus in combination, a sound receiver, a microphone comprising a cell having a flexible diaphragm, electrodes within the cell, one of 60 said electrodes being carried by the cell wall and another by the diaphragm, means connecting the diaphragm directly to the sound receiver, means supporting said cell for bodily movement with said sound receiver, and 65

a damping vane connected to said cell for opposing movement thereof, so that when said sound receiver moves slowly both of said electrodes are moved slowly with the sound receiver but without substantial relative movement therebetween and when the sound receiver moves rapidly the diaphragm-supported electrode is moved relatively to the other electrode, movement of the latter being opposed by said damping vane. 70 75

3. Sound detecting apparatus comprising a sound receiver, a microphone having two electrodes movable relatively to each other, means connecting one of said electrodes to said sound receiver so as to move with the receiver, the other electrode being connected to the sound receiver through the first electrode, and supporting means for the microphone independent of said sound receiver and constructed and arranged to permit 80 movement of said microphone in consonance 85 with the sound receiver.

4. Sound detecting apparatus comprising a sound receiver, a microphonic cell having two electrodes movable relatively to each other, means connecting one of said electrodes to said sound receiver so as to move with the receiver, the other electrode being connected to the sound receiver through the first electrode, and a pivoted arm supporting the cell so that it can move with the sound receiver. 90 95

5. Sound detecting apparatus comprising a sound receiver, a plurality of microphonic cells each having two electrodes movable relatively to each other, and a pivoted arm connecting one electrode of each cell to the sound receiver, the other electrode of each cell being connected to the sound receiver through the first electrode, whereby when 105 said arm is moved slowly by said sound receiver said cells are moved bodily without substantially any relative movement between the electrodes thereof and when said arm is moved rapidly said first electrodes are 110 moved relatively to said second electrodes. 100

6. Sound detecting apparatus comprising a sound receiver, a pivoted arm connected to said sound receiver, and a plurality of microphonic cells supported upon said arm 115 through the medium of their diaphragms.

7. Sound detecting apparatus comprising a sound receiver, a pivoted arm connected to said sound receiver, and a plurality of microphonic cells supported upon said arm 120 through the medium of their diaphragms equidistantly from the pivot of the arm.

8. Sound detecting apparatus comprising a sound receiver, a pivoted arm connected to said sound receiver, and a plurality of 125 microphonic cells mounted on said arm through the medium of their diaphragms equidistantly from the pivot of the arm and on opposite sides thereof.

9. A sound detecting device comprising 130

a pivoted lever arm provided with a support extending substantially at right angles to its longitudinal axis, and a plurality of similarly disposed microphones mounted in spaced relation upon said support.

10. A device of the class described having an oscillating lever arm, a series of microphone devices each comprising a cell and a

diaphragm, the cells and diaphragms of the series being arranged in alternation, and means connected to the several diaphragms whereby to support said microphones upon the lever arm.

Signed by me at Boston, Massachusetts, this twenty-ninth day of October, 1917.

WILLIAM L. WALKER.
